(57) **CLAIM**

The ornamental design for a container chassis as shown and described.

DESCRIPTION

FIG. 1 is a lower perspective view of a container chassis, showing my new design;

FIG. 2 is an upper perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof; and,

FIG. 8 is a top plan view thereof.

The appearance of any portion of the container chassis between the symbolic break lines, represented in alternating long and short dashed lines, forms no part of the claimed design. Features represented in dashed broken lines depict environmental subject matter and form no part of the claimed design.
